UNITED STATES PATENT OFFICE.

WILLIAM A. FANNING, OF CHICAGO, ILLINOIS.

WALL CONSTRUCTION.

Application filed March 7, 1928. Serial No. 259,785.

The invention relates to improvements in wall constructions and has for its primary object the provision of an improved construction of this character whereby building operations may be improved and cheapened.

Another object of the invention is the provision of an improved wall construction for buildings by means of which a stone, or imitation stone wall, may be constructed very economically.

Another object of the invention is the provision of an improved wall construction providing air spaces therein.

15 Other objects will appear hereinafter.

The invention consists in the combinations and arrangements of parts hereinafter described and claimed.

The invention will be best understood by 20 reference to the accompanying drawings forming a part of this specification and in which—

Fig. 1 is a side elevation, adjacent a corner, of a wall construction embodying the invention;

Fig. 2, a vertical section taken substantially on line 2—2 of Fig. 1;

Fig. 3, a horizontal section taken substantially on line 3—3 of Fig. 2;

30 Fig. 4, an interior elevation of a portion of the wall, and

Fig. 5, a perspective view of a portion of the wall.

The preferred form of construction as 35 illustrated in the drawings comprises outer courses of oblong blocks 6 laid alternately, as shown. The blocks 6 are preferably of stone, either natural or artificial, and, as shown, are made oblong in form, in the general form of a brick, but twice as large for 40 an eight inch wall. Thus the blocks 6 are made sixteen inches long, eight inches wide, and four inches thick. The blocks 6 are laid in the wall in courses, as shown, alternately sidewise and edgewise, that is, in one course with their broad faces horizontally and their longer edges exposed, the alternate course being arranged with the broad faces exposed.

45 The wall proper is laid upon a base or foundation consisting of an inner edgewise course of the blocks 6, and an outer course of specially prepared ornamental base blocks 7, as shown.

50 The inner portion of the wall is composed of inner courses of ordinary bricks 8, laid

endwise between the sidewise courses of the blocks 6, the bulk of the bricks 8 being set with their sides exposed so as to leave air spaces 9, as indicated.

When it is desired to break joints, as indicated in Fig. 4, or to provide spaces 10 for the reception of the ends of rafters 11, or the like, as indicated in Figs. 2 and 3, the adjacent bricks 8' are turned edgewise in the wall.

At the corners of a building, and in order to make the joints symmetrical, corner blocks 6' are employed in the sidewise courses of the blocks 6 which are three-quarters the 70 lengths of the normal blocks 6, thereby breaking joints as indicated. Otherwise the blocks 6' are the same as the block 6.

As indicated above, the blocks 6 and 6' are preferably of stone, either natural or 75 artificial, and the inner blocks 8, 8' are ordinary common bricks and may be used or second-hand bricks, thereby greatly cheapening the construction. The air spaces 9 thus provided in the wall have the usual insulating effect of such air spaces in building walls. By this arrangement, a wall which is practically as strong and durable as a solid wall, and has insulating air spaces therein, may be constructed at relatively small cost.

While I have illustrated and described the preferred form of construction for carrying my invention into effect, this is capable of variation and modification without departing from the spirit of the invention. I, 90 therefore, do not wish to be limited to the precise details disclosed, but desire to avail myself of such variations and modifications as fall within the scope of the appended claims.

I claim:

1. A wall construction comprising outer courses of oblong blocks having a width equal to the thickness of the wall, a length twice the width and a thickness one-half the 100 width, said blocks being laid in courses alternately sidewise and edgewise; and inner courses of oblong blocks having a length equal to the width of said first mentioned blocks, a width one-half the length and a thickness one-half the width, laid endwise between said sidewise courses, most of said inner blocks being laid with their widths exposed, but some being turned edgewise to break joints or provide space for rafters or 105 the like.

2. A wall construction comprising outer

courses of oblong blocks having a width equal to the thickness of the wall, a length twice the width and a thickness one-half the width, said blocks being laid in courses alternately 5 sidewise and edgewise, and corner blocks being interposed in said sidewise courses having lengths three-quarters of the length of the other blocks in said courses but otherwise the same; and inner courses of oblong 10 blocks having a length equal to the width of said first mentioned blocks, a width one-half the length and a thickness one-half the width, laid endwise between said sidewise courses, most of said inner blocks being laid with their 15 widths exposed but some being turned edgewise to break joints or provide space for rafters or the like.

3. A wall construction comprising outer courses of oblong blocks having a width equal

to the thickness of the wall, and a thickness one-half the width, said blocks being laid in courses alternately sidewise and edgewise; and inner courses of oblong blocks having a length equal to the width of said first mentioned blocks, a width one-half the length and a thickness one-half the width, laid endwise between said sidewise courses and, with the edges of said sidewise courses, completing the inner face of the wall, most of said inner blocks being laid with their widths exposed, 25 but some being turned edgewise to span and break the enclosed air space thereby leaving reinforced openings for the reception of the ends of rafters or the like.

In witness that I claim the foregoing as 30 my invention, I affix my signature this 2d day of March, A. D. 1928.

WILLIAM A. FANNING
